UNITED STATES PATENT OFFICE.

CHARLES WILLIAM COCHRAN, OF ATHENS, TENNESSEE.

ATTACHMENT FOR TELEPHONE-DESKS.

982,795.

Specification of Letters Patent. Patented Jan. 31, 1911.

Application filed March 12, 1910. Serial No. 548,903.

To all whom it may concern:

Be it known that I, CHARLES W. COCHRAN, a citizen of the United States, residing at Athens, in the county of McMinn and State 5 of Tennessee, have invented a new and useful Attachment for Telephone-Desks, of which the following is a specification.

This invention relates to improvements in attachments for telephone desks and the object of the invention is to provide simple and 10 efficient means whereby a pencil may be held within convenient reach so that the noting of telephonic messages may be proceeded with without delay.

15 The invention consists in certain novel features which are illustrated in the accompanying drawings, and will be hereinafter fully described and claimed.

In the drawings, Figure 1 is a perspective 20 view of a telephone desk showing my attachment in position thereon. Fig. 2 is a plan view of the pencil-holding attachment removed from the desk. Fig. 3 is a similar view showing a pencil held by the attachment. Fig. 4 is a detail sectional view of the device.

In carrying out my invention, I employ a base or block 1 having a plurality of outwardly-projecting arms or lugs 2 through 30 which securing screws may be passed into the telephone desk to secure the device rigidly in position thereon. The block 1 is preferably circular in form and is covered by a metallic plate 3 to prevent wear on the 35 same and to give it an ornamental appearance, the said covering plate being secured on the block by means of headed tacks or similar fastenings 4. Disposed centrally over the cover 3 is a spring coil 5, arched as 40 shown in Fig. 4, the convolutions of which extend on a curved line from end to end of the spring, as indicated by the dotted line 6—6 in Fig. 2, in a plane parallel to the top of the block and at a right angle to the plane 45 of the arch described by the spring and the ends of the wire from which the spring is formed are inserted through the block 1, as shown at 7, and have their extremities bent under the block, as at 8, whereby the withdrawal of the said ends of the spring from 50 the block will be positively prevented. The arching of the spring and the curving of the same between its ends render the device very efficacious as when a straight pencil is

inserted through the several coils, as indicated in Fig. 3, a strong frictional contact between the pencil and the inner surface of the several coils will be afforded so that the pencil will be firmly held and cannot be accidentally dislodged and lost.

My device is exceedingly simple and inexpensive, and the use of the same, together with its many advantages, are believed to be obvious and to need no further detailed mention.

From the foregoing description, taken in connection with the accompanying drawings, the advantages of the construction and of the method of operation will be readily apparent to those skilled in the art to which 70 the invention appertains, and while I have described the principle of operation of the invention, together with the device which I now consider to be the best embodiment thereof, I desire to have it understood that 75 the device shown is merely illustrative, and that such changes may be made when desired as are within the scope of the claims appended hereto.

Having thus described the invention, what 80 I claim as new, and desire to secure by Letters Patent, is:—

1. In combination with the base, a coiled spring having the terminals of the wire forming the spring secured to the base at 85 opposite sides of the spring and beyond the sides of the spring, said spring being arched above the base and also having its coils arranged on a curved line from end to end of the spring in a plane parallel to the top of 90 the base, the ends of the spring being open, whereby when a pencil is inserted longitudinally through the spring, frictional contact is established between the pencil and the coils of the spring.

2. A pencil-holding attachment for telephone desks consisting of a block provided with means for securing the same to the desk, and a coiled spring disposed above and secured to the block and having its coils so 100 disposed as to extend between its ends on a curved line in a plane parallel with the top of the block when not in use.

3. A pencil-holding attachment for a telephone desk consisting of a block adapted to 105 be secured to the desk, and a coiled spring arched over the block and having its coils extending between its ends on a curved line

in a plane at a right angle to the plane of the arch described by the spring, the ends of the spring being inserted through the block and turned against the under side of the block.

4. A pencil-holding attachment consisting of a block having means for securing the same to a desk or other support, and a coiled spring arched above the block and having its coils arranged on a curved line, the ter-

minals of the spring being extended in opposite directions and secured in the block.

In testimony, that I claim the foregoing as my own, I have hereto affixed my signature in the presence of two witnesses.

CHAS. WILLIAM COCHRAN.
